BAR MITZVAH TABLE ORNAMENT

Sara Rae Naimon, Milwaukee, Wis.

Application July 25, 1956, Serial No. 42,375

Term of patent 14 years

(Cl. D29—23)

Fig. 2.

Fig. 3.

Fig. 4.

The broken lines in the drawing are for the purpose of illustration only.

I claim:

The ornamental design for a bar mitzvah table ornament, as shown and described.
